COMPRESSOR UNIT

Dean C. Haggardt, Denver, Colo.

Application September 26, 1946, Serial No. 699,528

11 Claims. (Cl. 230—181)

1

This invention relates to new and useful improvements in compressor units.

One object of the invention is to provide an improved compressor unit for compressing fluids for use in refrigerators, temperature control, air conditioning and similar or allied mechanisms.

An important object of the invention is to provide an improved compressor unit wherein the compressor and its driving motor are incorporated in a single assembly, whereby a compact structure requiring a minimum space for installation is had and also whereby the unit includes a minimum number of working parts.

A particular object of the invention is to provide an improved unit, of the character described, wherein the compressor cylinder and its piston are mounted axially within an electric driving motor, with improved means for coupling the rotor of the motor to the compressor piston to impart reciprocation to said piston upon rotation of said rotor; the cylinder having suitable valved intake and exhaust ports which communicate with the line or coil through which the fluid to be compressed is circulated, whereby operation of the motor actuates the compressor piston to compress said fluid.

A further object of the invention is to provide a combination compressor and motor unit which functions as a two-stage compressor, whereby the fluid is first placed under pressure and is then finally compressed to the desired degree and recirculated through the refrigerating or other system; the two-stage compression providing for more efficient operation at less operating costs and with a minimum load on the compressor unit.

Still another object of the invention is to provide an improved device, of the character described, wherein the compressor piston element has its opposite ends of different cross-sectional areas whereby one end functions as a piston of relatively large area to displace a relatively large volume under low pressure of fluid and the opposite end functions as a second piston of smaller area to displace relatively small volume under high pressure of fluid, with the result that each reciprocation of said piston element accomplishes a two-stage compression of the fluid.

Another object of the invention is to provide an improved combination compressor and motor unit, of the character described, wherein the interior of the casing or housing of the motor functions as a chamber or reservoir for the fluid during the first stage of compression of said fluid, thereby eliminating the necessity of providing an auxiliary chamber for this purpose and permit-

2

ting the unit to be extremely small and compact in construction and also permitting the fluid being compressed to act as a lubricant for the compressor piston element as it reciprocates in its cylinder.

The construction designed to carry out the invention will be hereinafter described together with other features of the invention.

The invention will be more readily understood from a reading of the following specification and by reference to the accompanying drawing, wherein an example of the invention is shown, and wherein:

Figure 1 is a longitudinal, vertical, sectional view of a compressor and motor unit, constructed in accordance with the invention.

Figure 2 is an enlarged, sectional view of the exhaust end of the compressor cylinder.

Figure 3 is an enlarged, sectional view of the intake end of said compressor cylinder.

Figure 4 is a transverse, vertical, sectional view, taken on the line 4—4 of Figure 1.

Figure 5 is a transverse, vertical, sectional view, taken on the line 5—5 of Figure 1, and

Figure 6 is an isometric view of the compressor piston.

In the drawings, the numeral 10 designates a casing or housing which is substantially cylindrical and which has its ends closed by end plates 11 which are suitably bolted or otherwise secured thereto. Packing gaskets 12 interposed between the ends of the housing and the end plates 11 seal off the joint therebetween. The housing 10 is the casing or housing of an electric motor which includes a stator 13 mounted within the central portion of said housing. A double cylinder or tube 14 extends axially through the housing and has its ends supported in suitable supporting flanged collars 15 which are bolted or otherwise secured to the inner surface of the end plates. The cylinder is non-rotatable within the housing and forms a support or shaft on which the rotor 16 of the electric motor may rotate. As is clearly shown in Figure 1 the rotor includes a metal sleeve 17 which is rotatable around the cylinder 14 and suitable bearings 18 are interposed between the sleeve and the outer surface of the cylinder to facilitate such rotation. The cylinder is formed with an annular slot 20 at its central portion and an inwardly extending annular rib 21 which is formed on the metal sleeve 17 of the rotor is disposed within this slot to confine the sleeve and rotor against longitudinal movement on the cylinder.

The main bore 22 of the cylinder 14 is formed with a reduced portion 23, whereby an internal

55

annular shoulder 24 is provided within the cylinder. The main bore 22 provides a first stage cylinder while the reduced portion 23 comprises a second stage cylinder, with the first stage cylinder having communication with an inlet and the second stage cylinder communicating with an outlet, as will be explained. A double piston 25 is adapted to reciprocate within the cylinders 22 and 23. As is clearly shown in Figure 6 the main portion A of the piston 25 is of a diameter to fit within the first stage cylinder 22. The piston is formed with a reduced end B which is movable within the second stage cylinder 23 and the shoulder 26 formed on the piston is adapted to abut the shoulder 24 between the cylinders in one extreme position of the piston.

To impart a reciprocating movement to the piston upon a rotation of the rotor 16, the piston is formed with a helical or spiral groove 27 in its exterior surface. A ball member 28 which is confined within a radial opening 29 in the sleeve 17 of the rotor has its lower surface engaged within the groove 27, its upper surface being confined within the opening 29. The ball is retained in position by a suitable follower 30. Rotation of the piston 25 is prevented by engagement of a radial pin or projection 31 which is secured within the wall of the cylinder 14 and which projects into a longitudinal groove or recess 32 provided in the external surface of said piston.

It will be apparent that the piston 25 is non-rotatable within the cylinders 22 and 23 and when rotation is imparted to the rotor 16 by operation of the electric motor, the co-action between the connecting ball 28 and the helical groove 27 will impart a reciprocating motion or movement to the double piston. The helical groove is so disposed that complete reciprocation of the double piston will occur during one revolution of the rotor 16.

For admitting the fluid to be compressed to the intake end of the first stage cylinder 22, said cylinder is provided with an inlet opening 33. An inlet control valve 34 is mounted within this opening and has the fluid inlet pipe 35 connected thereto. As is clearly shown in Figure 3 the valve 34 is constructed so as to admit fluid into the cylinder but to prevent escape of fluid from the cylinder back into the inlet pipe. Thus, upon the intake stroke of the piston which is a movement of the piston 25 to the left in Figure 1, the valve 34 will be opened by the suction created by the piston and fluid will be drawn into the first stage of the cylinder.

Upon a reverse movement of the piston 25, that is, a movement to the right in Figure 1, the fluid which has been drawn into the first stage cylinder will be discharged through an opening 36 formed in the end plate 11 which closes the intake end of the piston. This opening has a check valve 37 which permits discharge of fluid from the cylinder but prevents entrance past said valve. A conductor 38 extends from the opening 36 and through the closure end plate 11 into the interior I of the housing 10. Thus, upon a movement of the piston to the right in Figure 1, the fluid is displaced through the conductor and into the interior of the housing. Because the first stage piston is relatively large, displacement of fluid from the cylinder through the conductor and into the housing will be in relatively large volume and under a relatively low pressure.

The interior of the housing communicates through a conductor or pipe 39 and a vertical passage 40 with the second stage cylinder 23. A

check valve 41 mounted in the passage 40 permits admission of fluid into the second stage cylinder through the passage but prevents the fluid from flowing from the exhaust end of the cylinder back into the interior of the housing. Therefore, as the piston moves to the right in Figure 1, the reduced portion B of the piston creates a suction which will draw fluid from the interior of the housing into the exhaust end 23 of the second stage cylinder. It will be remembered that this fluid is under some pressure having been placed under pressure by the large end of the piston 25 in the first stage cylinder 22. As the piston reciprocates back to the left in Figure 1, the reduced end B of the piston forces the fluid from the exhaust end of the second stage cylinder outwardly past a valve 42 mounted in the end of said cylinder and into a discharge pipe 43 which is connected in the end plate 11. The valve 42 is a check valve type and allows discharge of fluid from the cylinder while preventing admission into the cylinder from the pipe 43. It will be apparent that since the end B of the piston is relatively small in diameter and the cross-sectional area of the cylinder at the point is also relatively small, the fluid will be forced from the exhaust end of the second stage cylinder under a relatively high pressure and at a reduced volume. From the pipe 43, the compressed fluid is circulated through the refrigerating or other system with which the device is used.

The operation of the combined compressor and motor unit is believed obvious. Beginning the cycle with the parts shown in Figure 1, it will be apparent that as the rotor 16 rotates, the piston 25 will be moved toward the left in this figure. This movement will cause the smaller end B of the piston which forms the second stage piston to discharge the fluid under desired compression through the outlet 43, the discharge fluid having been drawn into the second stage cylinder upon the preceding operation of the piston. As said piston moves to the left, the second stage piston discharges fluid under desired compression and the larger end of said piston forming the first stage piston creates a suction in the intake end of the first stage cylinder 22, whereby additional fluid is drawn through the inlet pipe 35 past the valve 34 into said intake end of the first stage cylinder.

Continued rotation of the rotor 16 causes the piston to reach the extremity of movement toward the left after which the piston moves back to the right in Figure 1; as this occurs, the fluid which has been drawn into the first stage cylinder 22 is forced outwardly through the conductor 38 and into the interior of the housing. As explained, this displacement is of a relatively large volume and under some pressure so that this comprises a first stage of compression of the fluid. At the same time that fluid is forced into the interior of the chamber through the conductor 38, additional fluid is drawn from the interior of the housing through the conductor 39 and vertical passage 40 into the second stage cylinder 23. This fluid which enters the second stage cylinder is under the pressure which the larger end of the piston has created and thus the fluid is ready for the second stage of compression. This second stage is accomplished when the piston again moves back to the left in Figure 1 to begin the next cycle of operation.

The two-stage compression provides for exceptionally efficient operation since the compression may be accomplished with less power. The

entire unit is simple and compact in construction, with the compressor unit being incorporated within and substantially forming a part of the electric motor. There is only one moving part, which is the double piston, in the entire device and the circulation of the fluid through the housing, which forms a first stage compression chamber allows the fluid to lubricate the piston and rotor. It is noted that the particular ball 28 which is used to transmit the reciprocating movement to the piston is employed because it minimizes friction; however, a radial pin would serve the same purpose. The valves that are shown are merely for the purposes of illustration and any suitable check valve device could be employed. The main feature of the invention is the two-stage compression which makes for maximum efficiency with minimum operating costs.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A compressor unit including, an electric motor comprising a sealed housing having a stator and a rotor therein, a compressor tube forming a pair of aligned cylinders which cylinders provide a first and second stage of compression extending axially through the rotor and having its ends supported in said housing and forming a support on which the rotor may rotate, a piston reciprocable within said cylinders, means for coupling the rotor to the piston whereby rotation of said rotor imparts reciprocation to the piston, a valved intake inlet at one end of the first stage cylinder for admitting fluid to said cylinder, means for establishing communication between the cylinders, and a valved exhaust outlet at the exhaust end of the second stage cylinder for discharging the fluid under compression.

2. A compressor unit as set forth in claim 1, wherein the means for establishing communication between the cylinders is the interior of the motor housing and passages connecting the cylinders with said interior.

3. A compressor unit as set forth in claim 1, wherein the means for establishing communication between the cylinders is the interior of the motor housing and passages connecting the cylinders with said interior and valves mounted in said passages, whereby as the fluid is forced into the interior of the housing from the first stage cylinder it is placed under its initial stage of compression, the second stage of compression being completed when the fluid from the interior of the housing is discharged from the exhaust end of the second stage cylinder.

4. A compressor unit including, an electric motor comprising a sealed housing having a stator and a rotor therein, a compressor tube forming a first stage cylinder and a second stage cylinder extending axially through the rotor and having its ends supported in said housing, the tube forming a support on which the rotor may rotate, a piston reciprocable within said cylinders, means for coupling the rotor to the piston whereby rotation of said rotor imparts reciprocation to the piston, a valved inlet in the intake end of the first stage cylinder for admitting fluid into the cylinder, a passage extending from the first stage cylinder to the interior of the motor housing whereby fluid from said cylinder is exhausted into

the housing, a second passage connecting the interior of the motor housing with the second stage cylinder to admit fluid from said housing to that cylinder, and a valved discharge outlet leading from the second stage cylinder for discharging fluid under compression from the cylinder.

5. A compressor unit as set forth in claim 4, wherein back-pressure valves are mounted in the passages connecting the interior of the housing and the cylinder ends, whereby flow in only one direction from the first stage cylinder, through the housing and into the second stage cylinder is possible.

6. A compressor unit as set forth in claim 1, 15 wherein the bore of the compressor tube forming the second stage cylinder is reduced and also wherein the piston has a reduced portion reciprocable in said second stage cylinder, whereby the fluid displaced by that end of the piston operating within the second stage cylinder is greater in volume than that displaced by the other end of said piston.

7. A compressor unit as set forth in claim 1, 25 wherein the means for coupling the rotor to the piston is a projection on the rotor and a helical groove on the exterior of the piston, together with co-acting means on the piston and cylinders for preventing rotation of the piston, whereby a rotation of said rotor assures reciprocation of 30 the piston.

8. A compressor unit including, an electric motor comprising a sealed housing having a stator and a rotor therein, a compressor tube forming a first stage cylinder and a second stage cylinder 35 and extending axially through the rotor with its ends supported in the housing, the cylinder forming a support on which the rotor may rotate, the cross-sectional area of the bore of the first stage cylinder being greater than the cross-sectional area of the second stage cylinder, a dual piston slideable within the cylinders and having a reduced end portion movable within the second stage cylinder, means for coupling the piston to the rotor whereby rotation of the rotor imparts 40 reciprocation to the piston, a valved inlet for admitting fluid to the first stage cylinder, a chamber communicating with the outlet of the first stage cylinder, whereby fluid admitted to the cylinder is displaced into the chamber in a relatively large volume and under a relatively low pressure, means for establishing communication between the chamber and the second stage cylinder whereby the fluid from said chamber may be admitted to the cylinder, and a valve outlet 45 connected to the exhaust end of said second stage cylinder, the displacement of the fluid from the second stage cylinder being under relatively greater pressure and lesser volume due to the reduced area of the cylinder and piston operable 50 therein.

9. A compressor unit as set forth in claim 8, 55 wherein the chamber is the interior of the motor housing which communicates with the ends of the cylinders through suitable flow passages.

10. A compressor unit as set forth in claim 8, 60 wherein the chamber is the interior of the motor housing which communicates with the ends of the cylinders through suitable flow passages and check valves in said passages for permitting flow 65 in one direction only, whereby the fluid is displaced from the first stage cylinder, through the interior of the housing, then to the second stage cylinder and finally discharged therefrom through the valved outlet.

11. A compressor unit as set forth in claim 8,

wherein the means for coupling the rotor to the piston is a projection on the rotor and a helical groove on the exterior of the piston, together with co-acting means on the piston and cylinder for preventing rotation of the piston, whereby a rotation of said rotor assures reciprocation of the piston.
